UNITED STATES PATENT OFFICE.

NATHAN KASDAN, OF NEW YORK, AND DANIEL POLLACK, OF BROOKLYN, NEW YORK.

ARTICLE-CONTAINING CASE.

Application filed February 18, 1926. Serial No. 89,021.

This invention relates to article containing cases and more particularly, but not necessarily, to vanity cases of a thin model type. One of the objects of the invention is to provide an article containing case with an improved hinge construction, whereby the appearance of the case is rendered neat and attractive when the casing sections are closed. Another object of the invention is to provide an improved hinge construction wherein the pintle is preferably formed integrally with one of the casing sections, or some other section or member of the case, as by means of a slot formed in an annular bead, for example, on one of the casing sections, which slot is so formed as to leave a certain amount of stock of the bead at a point to the outer side of the slot, whereby the pintle is formed integrally with said bead at the margin thereof, the other casing section being hinged on said pintle. Another object is to provide a simple and efficient means for retaining a mirror in the case. These being among the objects of the present invention, the same consists of certain features of construction and combinations of parts to be hereinafter described and then claimed with reference to the accompanying drawings illustrating several embodiments of the invention, in which:

Fig. 1 is a plan of the article containing case in which the sections are swung to open position;

Fig. 2 is a section on the line 2—2 of Fig. 1;

Fig. 3 is an enlarged section of the closed case;

Fig. 4 is a section on the line 4—4 of Fig. 1;

Fig. 5 is a still further enlarged section, part broken away, of the closed case for the purpose of showing more clearly the preferred construction of hinge, as well as other details;

Fig. 6 is a broken detail of one of the casing sections showing a preliminary step in the method of providing a hinge, the slot being shown as curved;

Fig. 7 is a similar detailed view in which the slotted portion of the case has been

shown as straightened in order to provide a proper pintle;

Fig. 8 is a plan view of a modification illustrating another adaptation of the improved hinge construction;

Fig. 9 is an exploded view of the hinge construction, the main parts of the case, etc. being broken away;

Fig. 10 is an enlarged transverse section of the hinge construction shown in Figs. 8 and 9;

Fig. 11 is an exploded plan view of another modified hinge construction with the parts broken away;

Fig. 12 is an assembled view, in section, of the improved hinge construction illustrated in Fig. 11; and

Fig. 13 illustrates a modification in one of the casing sections.

Referring to Figs. 1, 2, 3 and 5, the thus illustrated article containing case comprises a section 10 and a section 11, each of these casing sections being preferably composed of thin sheet metal. Preferably, the sections are not very deep in order that when the sections are closed together a thin model case is provided, although the invention is not limited to depth, shape or the like. Each of the casing sections is preferably of shallow, dished form, as is clear from Fig. 2, the sections being preferably connected together by hinge construction 12. The casing section 10 is shown as provided with a rim 13 which is adapted to snugly fit within the rim of the casing section 11 when the sections are closed together, as shown in Fig. 3. In other words, the width or diameter of the rim 13, across the case, is such that the rim of the casing section 11 will preferably snugly fit or telescope thereover when the casing sections 10, 11 are closed together, whether or not the sections be connected by a hinge.

At the side of the case opposite to the hinge 12, the sections 10, 11 are respectively provided with a slight recess or notch 14 and a slight keeper projection 15 so that a snap fastening is provided to hold the two sections closed together. A slight projecting ledge or lip 16 is provided on section 11, whereby to facilitate the opening of the cas-

ing sections when they are snapped to closed position. As before intimated, the casing sections 10, 11 may be of any suitable construction and shape or size, but when the 5 case is made in the form of a vanity case, the section 10 is adapted to retain in it a shell or tray 17 which holds the compact 18, while the other section 11 is adapted to retain the frame 19 of a mirror 20. Or, the 10 contents may be arranged and mounted in any other manner. The casing section 11 is preferably provided with a series of slight inwardly struck, opposed teats 21, see also Fig. 4, which are arranged at a median 15 plane parallel with the plane in which the said casing section extends and are spaced apart in such plane, and when the mirror and its frame 19 are pressed firmly into the casing section 11 the outer edge of the frame 20 is caused to have a snap engagement with the inwardly presented shoulders of said teats 21. As shown more clearly in Fig. 4, each 25 inwardly presented shoulder is more or less square or abrupt so as to positively act to hold and lock the mirror frame in place when it is sprung against the inner surface of the casing section.

By referring more particularly to Figs. 1, 5, 6 and 7, the construction of the preferred hinge will be more clearly understood. Inasmuch as the invention is more particularly adapted for vanity cases which should be attractive at least, if not simple and plain, the casing section 10 is provided 30 with an annular finishing bead or outwardly extending portion 22. This bead is preferably continuous and formed bodily out of the thin metal of said casing section; that 35 is to say, the bead is double ply and substantially solid due to the fact that the thin sheet metal is actually deformed bodily and the two plies compressed together, whereby 40 the bead is folded longitudinally so that the fold line is at the outer margin of the bead 45 or outwardly extending portion. Such outwardly extending portion of casing section 10 is located at a median plane thereof parallel with the plane in which said casing section extends.

50 In its original form, the bead is preferably circular throughout, if the article containing case is to be circular. When the bead is circular or curved, a slot 23 is preferably cut or slashed through the compressed 55 double thicknesses of the bead, as shown in Fig. 6. This slot or cut-out is seen to be slightly curved, that is, arcuate, and is concentric with the curvature of the outer margin of the bead. The reason for the curving 60 of the slot when the bead is curved is that it preferably is desired to leave a portion of the stock of the bead at the outer margin of the bead, which stock portion is of the same thickness from end to end of the slot. 65 After the arcuate slot 23 has been cut

through the bead, the stock of the metal of the casing section 10 at both sides of the slot is straightened, whereby the slot which was previously curved now appears as a straight slot 24, while the portion of the 70 stock of the bead at the outer side of the slot has also been straightened and will constitute a straight pintle 25, as shown in Fig. 7. Therefore, in this adaptation of the invention, a short portion of the continuous 75 annular bead 22 will be straightened in the location of the pintle 25. In this or some such manner, a pintle 25 may be provided which is in one piece or integral with the entire casing section 10. The casing section 80 11 is provided with an extension integral therewith, which is bent around the pintle 25 to provide a hinge knuckle 26.

When a case is constructed as described 85 with reference to Figs. 1 to 7, and the casing sections or members 10, 11 are closed together, the rim of section 11 will engage over the rim 13 of the other section and will abut against the inner peripheral portion of the bead 22, so that the line of separation between the said sections will be located at the points where the bead 22 and the section 11 meet, and the bead will protrude beyond the line of separation.

90 It will be observed that the improved hinge construction thus described lends itself most admirably to a vanity or other case provided with an annular outwardly extending bead, as preferably a portion of the bead may be utilized as a hinge pintle, which not only provides a very simple and reliable hinge construction but contributes to the attractiveness of the case.

95 Viewing the described hinge construction somewhat differently, it will be observed 105 that the edge portion 22 of the section or member is of considerable or minimum thickness, is substantially solid, and that it is cut out or a portion removed in such way as to leave a cut-out or recess extending along it, 110 a pintle being provided at the outer side of the cut-out, forming an unbroken continuation of the margin of the edge portion, whereby an improved hinge connection may 115 be made with the knuckle of another section or member of the case, and in which the pintle is not necessarily inset from such margin.

120 Referring to the modification illustrated in Figs. 8, 9 and 10, a casing section 31 of the case is provided with hinge knuckles 32, 33 which are suitably spaced apart. A pintle 34 on the other casing section 35 receives the knuckles 32, 33 whereby the casing sections 31 and 35 are hinged together. Casing section 35 is provided with an outwardly extending portion 36 preferably forming a bead around said section, and the bead is provided with a cut-off 34^a forming 125 a slot between the pintle 34 and the rim 130

of the casing section 35, which rim is adapted to receive the rim of the casing section 31 which engages over it. In this form of the invention, the pindle 34 also constitutes an unbroken continuation of the margin of the outwardly extending portion or bead 36, and this portion of the hinge may be constructed as before described.

The casing section 31 is adapted to receive a tray 37, which is held thereon by snapping it into engagement with a series of inwardly projecting teats 38, said tray serving to hold a compact 39 of face powder. The other casing section 35 may also in obvious manner be adapted to receive a container or tray for another kind of face powder. Of course the casing sections 31 and 35 may be adapted to receive whatever is desired to be held in the vanity case or other case, according to requirements.

An intermediate, movable member or section 40 is arranged between the casing sections 31, 35 and said member or section 40 may be of any suitable construction and is provided with a hinge knuckle 41, which is located between the hinge knuckles 32, 33 and through which the pindle 34 also passes, whereby the member or section 40 is hinged so that it may be swung with or towards either of the casing sections 31, 35. Preferably, the swinging member or section 40 supports a frame 42 for holding a mirror 43. Both surfaces of the member or section 40 may carry mirrors, or one of the surfaces 35 may carry a mirror and the other surface a compact, tintype, or whatever is desired.

Casing section 31 is provided with an outwardly projecting lip or thumbpiece 44. The casing sections 31, 35 are adapted to be held together by a snap fastening comprising an inwardly projecting teat 45 adjacent the lip 44, and which is adapted to engage a cavity 46 in the rim of the casing section 35. Preferably, the intermediate swinging section 40 is provided with an outwardly extending lip or thumbpiece 47, so located that when the vanity or other case is closed said lip 47 will be placed in juxtaposition to the lip 44 on the casing section 31. The rim of the casing section 35 has a recess 48 so located that when the member or section 40 is swung against the casing section 35 its lip 47 will be received in the recess, whereby when the casing sections are moved so as to close them together, the lip 47 will not interfere with the closure.

It will be observed that when the case is closed, the lip 47 of the swinging member 40 will be located in a plane between the planes of the lip 44 on the casing section 31 and the bead or outwardly extending portion 36 on the other casing section. The construction and the arrangement of the just described parts is obviously such that the user of the case may engage the thumb of

one hand with the lip 47 and the thumb of the other hand with the lip 44 and open the casing section 31, leaving the member or section 40 in place against the casing section 35. Also, by engaging the thumb of one hand with the lip 47 of the swinging member 40 and the thumb of the other hand with the outwardly extending portion or bead 36, the case may be opened in such way as to carry the swinging member 40 with the casing section 31 instead of with the casing section 35.

Referring to the modification shown in Figs. 11 and 12, which illustrate but fragments of a complete case, it will be understood that the casing section 49 is provided with hinge knuckles 50, 51 and the casing section 52 is provided with a hinge knuckle 53 which is located between the hinge knuckles 50, 51 when the parts are assembled as in Fig. 12. Through the hinge knuckles 50, 51, 53, there passes a pindle 54 on the intermediate swinging member or section 55. In this form of the invention it will be seen that the hinge construction is substantially as before described, except that the pindle 54 is on the intermediate swinging member or section instead of on one of the casing sections. The intermediate swinging section 55 may be in the form of a ring or frame, and at one of the two faces thereof it may have an inward flange 56. The flange 56 may constitute a seat against which to rest a mirror 57 or other article, while a container or tray 58 for a powder compact 59 may be engaged within the frame 55 so as to face in opposite direction to the mirror or other article 57. Of course, the swinging frame section or member 55 may contain a mirror and a compact, as shown, or may be used for containing other articles, but when used for containing a mirror and compact the casing sections 49, 52 may be used for supporting other devices and articles. Of course, the casing sections 49, 52 may be used for holding compacts, or if there is no mirror in the swinging frame section 55 a mirror may be placed in each of the casing sections 49, 52.

Referring to Fig. 3, a modification of such section or member as is provided with the outwardly extending portion or bead, such as referred to, is illustrated. In this modification the casing section 60 is composed of two pieces, and the bead or outwardly extending portion 61 is also in two pieces. This may be done in various ways, as is obvious. As illustrated, the rim 62 of the casing section 60, which rim is at the inner periphery of the bead 61, is provided with an outwardly extending flange 63 over which there is turned and spun a flange 64 which is doubled back on itself over the flange 63. In some such way a seam and union is provided between the main body of the casing

section 60 and its rim 62. Also, the bead or outwardly extending portion 61 is substantially solid in that same is compressed so that the different plies thereof are brought 5 into contact. By constructing the casing section 60 in two pieces, it is obvious that it may be adapted for other utilitarian purposes than when such casing section is made of one piece.

10 The invention is susceptible of modification, as parts of the same may be variously modified, as will be obvious to the skilled mechanic, without departing from the spirit and scope of the invention as expressed in 15 the appended claims.

Having thus described our invention, what we claim is:

1. In a device of the character described, 20 two sections, one of which is provided with a substantially solid bead having a slot extending along the same, a pintle at the outer side of the slot and formed by the margin of the bead thereat, and the other of which sections is provided with a knuckle which receives said pintle, whereby a hinge-joint is provided between said sections.

2. In a device of the character described, 30 two casing sections of thin metal one of which is provided with a bead with a compressed fold and formed bodily from that section, whereby a bead of minimum thinness is provided with a fold longitudinal thereof, said bead having a slot extending along the said fold, a pintle at the outer side of the slot and 35 formed by the balance of the bead thereat, and the other of which sections is provided with a knuckle which receives said pintle, whereby a hinge-joint is provided between said sections.

40 3. In a device of the character described, two casing sections one of which is provided with an outwardly extending portion integral therewith, and the wall proper of said section being free from mutilation due 45 to the presence of the outwardly extending portion, said outwardly extending portion having a slot and that part thereof which is between the slot and the edge of said portion constituting a marginal pintle, and 50 the other of which casing sections is provided with a knuckle which receives said pintle, whereby a hinge-joint is provided between said sections.

4. In a device of the character described, 55 two circular casing sections each of which is of shallow, dished form and consists of thin metal, and fitted one to the other, one of the sections having an annular bead consisting of an outward bodily deformation of the thin metal, whereby the bead is folded longitudinally, said folded bead being compressed and having a slot extending through the entire thickness thereof, and a pintle 60 outward of the slot and which is formed by the stock of the bead there remaining, and

the other of which sections is provided with a knuckle which receives said pintle, whereby a hinge-joint is provided between said sections.

5. In a device of the character described, 70 two fitted casing sections, one of which is provided with a pintle integral therewith, and located outward of the wall proper thereof, and the wall proper of said section being free from mutilation due to the presence of the pintle, and the other of which sections is provided with a knuckle which receives said pintle whereby a hinge-joint is provided between said sections.

6. A shallow dished section of thin metal, 80 a bead consisting of an outward bodily deformation of the thin metal, whereby the bead is folded longitudinally, said folded bead having a slot extending through the thickness thereof, and a pintle outward of 85 the slot and which is formed by the stock of the bead there remaining.

7. A casing section of thin metal having integral therewith a pintle consisting of a linear portion of the surrounding margin 90 of the said section, which pintle is located outward of the wall proper of the casing section, and the wall proper of said section being free from any mutilation due to the formation of said pintle.

8. In a vanity case, two metallic casing sections, the outer wall of one of said sections having a series of opposed slight inwardly projecting teats arranged in a median horizontal plane of said section and spaced apart in such plane, said teats being struck up from said section and having abrupt, squared shoulders presented inwardly of the section, and a mirror provided with a frame which may be snapped into 100 said section for the engagement of the said shoulders with the edge of said frame.

9. In a device of the character described, 110 a plurality of sections, the edge of one of which is reduced to minimum thinness and is substantially solid, and provides a marginal portion, which is cut away to leave a cut-out extending along the same, the cut-out being outward of the wall proper of the said section, a pintle at the outer side of the cut-out, and another of which sections is provided with a knuckle which receives said pintle, whereby a hinge-joint is provided between said sections.

10. In a device of the character de- 120 scribed, a member having its marginal portion cut away lengthwise thereof, the cut-out being outward of the wall proper of the member, and a pintle defining the outer side of the cut-away and forming an unbroken continuation of the edge of the marginal portion, whereby a slot is provided for receiving a hinge-knuckle.

11. In a device of the character de- 130 scribed, a casing section or member having

its marginal portion cut away lengthwise thereof, and a pintle defining the outer side of the cut-away and forming an unbroken continuation of the edge of the marginal portion, whereby a slot is provided for receiving a hinge-knuckle, said section having a rim projecting outwardly from the inner

periphery of the marginal portion, in combination with a second casing section hinged on the pintle, said sections having snap fastening means to hold them together. 10
